BUSHING FOR DRUMS

Charles E. Farrington, Phoenixville, Pa.

Application June 1, 1935, Serial No. 24,485

4 Claims. (Cl. 285—50)

This invention relates to agitator drums and more particularly to a method and means for equipping ordinary drums with agitator devices for effectively stirring and mixing the contents 5 of the drums so equipped.

Agitator-equipped drums for transporting paints and other such liquid or semi-liquid compounds are now well-known in the art and are quite generally employed. Such drums are disclosed in my own prior Patents No. 1,336,830, granted April 13, 1920, and No. 1,970,367, granted 10 August 4, 1934, from which it will be observed that the upper and lower heads thereof are respectively adapted to receive and maintain in 15 proper operating position therebetween an agitating device in the form of a stirrer bar of suitable design. It will be appreciated, of course, that the most expensive element of the agitator-equipped drum is the drum itself, the cost of 20 which to produce is quite a considerable item. These drums, which are generally of a 55-gallon capacity, are usually constructed entirely of sheet metal of sufficiently heavy gauge to adequately withstand the pressure of the contents thereof. 25 Moreover, the top and bottom drumheads are welded or otherwise so permanently secured to the side walls thereof that it is the general practice to prepare the drumheads for proper reception of the agitating device preliminarily and 30 prior to the operation of securing the drumheads in position.

I have found that there is available in the open market an exceedingly large number of second-hand or used ordinary drums which have never 35 been provided with agitator devices but which are nevertheless well adapted to be reconditioned to accommodate agitators of the type disclosed in my prior patents aforesaid. When so reconditioned and equipped with agitators, these 40 drums serve admirably as transport containers for paints and other liquid and semi-liquid compounds. When it is realized that these used drums may be purchased at a cost so far less than that of a new drum that even when reconditioned 45 to include agitator devices, the total cost of each reconditioned drum is materially less than the cost of producing a completely new agitator-equipped drum, it will be evident that a considerable saving is effected without any decrease in 50 the efficiency of operation of the reconditioned drum. To effect this saving is one of the principal objects of the present invention.

Among the further objects of the present invention is to provide an exceedingly simple and 55 effective method of adapting the upper head of a

standard drum for the reception of a stirrer bar without involving the necessity of removing the said head from the drum body nor the necessity of employing any relatively expensive or complicated tools or equipment.

A further object of the invention is the provision of members which are so operatively related to each other as to permit their ready securement to the drum head of a standard drum in such manner as to provide a bung hole assembly in the said drumhead through which a stirrer bar may be inserted for operative disposition within the drum, as well as to the side wall of the drum adjacent the bottom thereof to provide a faucet opening, the said parts being of 15 such order that they may be operatively assembled either upon the drumhead or upon the side wall of the drum without necessitating the removal of either drumhead from the drum body and without requiring any alteration or modification thereof other than to provide in the upper 20 head and side wall of the drumholes or apertures of requisite diameter.

Other objects of the invention and advantages resulting therefrom, as well as economies effected 25 thereby, will be apparent more fully hereinafter, it being understood that the invention consists substantially in the combination, construction, location and relative arrangement of parts, as well as in the method of assembling the same, 30 all as is more fully described hereinafter, as is shown in the accompanying drawing, and as is finally pointed out in the appended claims.

In the accompanying drawing, which illustrates and exemplifies a preferred embodiment 35 of the present invention:

Figure 1 is a vertical sectional view of a standard drum reconditioned in accordance with the present invention;

Figure 2 is an enlarged diametrical sectional 40 view of the bunghole assembly as installed in the upper head of the reconditioned drum;

Figure 3 is a plan view of one of the members of the bunghole;

Figure 4 is a view showing the manner of projecting the said member through the apertured drumhead into operative position;

Figure 5 is a view showing the several parts of the bunghole fitting in the process of being operatively assembled upon the apertured drumhead; 50 and

Figure 6 is a view showing the several parts of the bunghole fitting completely assembled and with the assembling tool still in position.

Referring now more particularly to the draw- 55

ing, it will be observed that the present invention contemplates the reconditioning of a standard type drum 10 to accommodate within the interior thereof an agitating device, preferably of the type designated by the reference numeral 11. The drum which is so adapted to be reconditioned is of the more or less conventional type having the opposed upper and lower drumheads 12 and 12a which are welded or otherwise permanently secured to the side walls 12b of the drum. These drums are of the type such as are generally employed for transporting oil and other liquid or semi-liquid compounds and are usually characterized in that they are provided with a bung-hole located in the side wall of the drum or in one or the other of the drumheads adjacent the peripheral margin thereof. In order to operatively accommodate an agitating device in the form of a stirrer bar, like that designated by the numeral 11 in Figure 1, within the interior of the drum, it is, of course necessary to provide coaxial bearings in the opposed drumheads 12 and 12a of the drum for respectively receiving the opposite extremities of the stirrer bar which is designed for rotation about the common vertical axis of the vertically spaced bearings.

To this end, the upper head 12 of the drum is centrally cut out to provide an opening 13 there-in of a diameter sufficient to permit the agitating device 11 to be freely projected therethrough into the interior of the drum. This agitating device 11, which may be of any desired form, is, in the present exemplification of the invention, in the form of a relatively thin elongated flat bar or blade the central portion 14 of which is radially offset from the coaxially opposed extremities 15 and 16 thereof. The upper extremity 15 of the stirrer bar is arranged for vertical projection through the opening 13 of the upper drumhead 11 of the drum, while the lower extremity 16 thereof is adapted to be pivotally anchored upon a pivot pin or stud 17 secured to the bottom 12a of the drum in vertical alignment with the central axis of the opening 13. The centrally offset portion 14 of the stirrer bar is twisted upon itself to facilitate the stirring and mixing of the compound contained within the drum when the stirrer bar is rotated about its vertical axis of rotation. In order to effect this rotation of the stirrer bar the upper extremity thereof is adapted to be engaged by an operating handle (not shown) of the types more particularly disclosed in my prior patents aforesaid, it being a characteristic feature of these handles that the blade engaging portion thereof is adapted to be journaled within the bung hole fitting, the several parts of which are operatively assembled together and secured to the marginal edge of the opening 13 in the manner and by the means now to be described.

As appears most clearly in Figures 2 to 6, inclusive, this bunghole assembly essentially comprises a crescent-shaped split ring member 18, a bushing 19 and a bunghole cap or closure member 20. The crescent-shaped member 18 is in reality in the form of a disk of substantial thickness in which is provided an interiorly threaded opening 21 located eccentrically with respect to the central axis of the disk. The marginal wall of the opening 21 is split, as at 22, at the point of its smallest radial dimension, the separation between the terminal extremities 23-24 of the split ring being merely sufficient to permit the portion of the drumhead 12 which marginally surrounds the central opening 13 therein to be accommodated between the said terminal extremities 23-24

when the ring 18 is manipulated into the position shown in Figure 4.

It will further be observed, as appears most clearly in Figures 3 and 4, that the split ring member 18 is of maximum radial dimension at the point substantially diametrically opposite the free terminal extremities 23-24 thereof. The bushing 19 is provided with a depending annular flange 25 which is exteriorly threaded, as at 26, and in addition is provided with a radially extending flange 27. The central opening of the bushing is interiorly threaded, as at 28, to threadedly receive the bunghole cap or closure member. As appears most clearly in Figure 2, the bushing 19 is adapted to be threadedly connected to the split ring member 18 in such manner as to clampingly engage the marginal edge of the central opening 13 in the drumhead between the upper face of the member 18 and the lower face of the radial flange 27 of the bushing. In order to accomplish this, the split ring member 18 must, of course, be positioned beneath the drumhead 11 in such manner that the interiorly threaded opening 21 thereof is in coaxial registry with the central opening 13 in the drumhead. This is effected by the use of a tool 29 of the type shown in Figures 5 and 6 and which is in the form of a spring steel strap doubled upon itself to provide a pair of branches 30 and 31 the lower ends of which are respectively provided with outwardly turned terminal extremities 32 and 33. Due to the inherent resiliency of the material of which the tool 29 is formed, the branches 30-31 thereof tend constantly to spring away from each other into the full-line position shown in Figures 5 and 6.

To assemble the split ring member 18 and the bushing 19 securely together in the relation shown in Figure 2, the split ring 18 is first threaded through the central opening 13 of the drumhead 12, this being accomplished most expeditiously by initially inserting one of the terminal extremities 23-24 thereof into the said opening 13 and then rotating the split ring member 18 in such manner as to locate the said member entirely beneath the drum head 12. The tool 29 is then also inserted through the opening 13 in the drum as well as through the interiorly threaded opening 21 of the split ring, this being accomplished by pressing the branches 30-31 of the tool together sufficiently to permit the terminal extremities 32-33 to pass freely through the said registering openings 13 and 21. Upon releasing the branches 30-31 they spring apart sufficiently to cause the terminal extremities 32-33 thereof to underlie and engage diametrically opposed portions of the under surface of the split ring 18 in such manner that as the tool 29 is drawn upwardly, the split ring 18 is held firmly against the bottom surface of the drumhead 12 with the threaded opening 21 of the member 18 in axial alignment with the central opening 13 of the drumhead.

While the tool so engages and retains the split ring 18 in position, the bushing 19 is slipped over the tool 29 (see Figure 5) and downwardly thereof for threaded engagement with the split ring 18, it being apparent that as the bushing is threadedly secured to the split ring, the arms 30-31 of the tool 29 are gradually compressed inwardly and toward each other into the dotted line position shown in Figure 5. When the bushing 19 is threadedly secured to the split ring member 18 sufficiently to provide a "finger-tight" hold between these parts, the placer tool 29 is removed,

following which a wrench may be applied to the bushing 19 to effect a leak-tight threaded connection between the members 18 and 19. Preferably, gaskets 30a and 30b are respectively disposed upon opposite sides of the drum head 12 to insure an absolutely leak-tight connection between the threadedly connected members 18 and 19. Due to the particular shape and construction of the split ring member 18, including as it does a zone of maximum strength in the portion thereof which is diametrically opposite to the free extremities 23-24 thereof, it will be evident that very considerable power may be applied to the bushing 19 in effecting the leak-tight connection without incurring any danger of cracking or otherwise weakening the split ring member, this being due to the fact that the point of greatest strain in this latter member has been substantially reinforced.

With the parts 18, 19 and 30a secured together and to the drum head 12 in the manner just described, it will be apparent that the drum 10 is as fully and completely adapted for reception of an agitating device as though it had been originally specially designed and constructed to receive the latter. Not only is a very considerable saving effected due to the saving in cost of the drum itself but there is also effected a considerable saving in the cost of equipping the upper head of the drum with the bung hole assembly due to the fact that the several parts of this assembly are mechanically assembled and secured together by the use of simple and inexpensive tools.

As will be obviously appreciated, the bunghole fitting or assembly of the present invention may vary structurally to adapt it to different types of stirrer bars and operating handles therefor. Thus, the bushing member 19, which in each instance is designed for threaded engagement with the split ring member 18 in such manner that the said members 18 and 19 clampingly engage opposite faces of the drumhead 12, may be designed to removably carry a stirrer bar supporting pin 45 of the type disclosed in my pending application Serial No. 663,739, filed March 31, 1933. Inasmuch as this supporting pin forms no part of the present invention, it is deemed unnecessary to describe it in detail herein, it being mentioned merely to illustrate the adaptability of the present invention to various arrangements and styles of agitator-equipped drums.

The bunghole assembly as hereinbefore described is, of course, not limited in its application to the drumhead alone, but instead may be employed in any other part of the drum to provide therein an interiorly threaded opening for receiving any desired type of fitting. For example, the assembly of the present invention may be provided in the side wall of the drum adjacent the bottom thereof, as at 34, for the reception of a

faucet (not shown) through which the contents of the drum may be removed.

It will be understood, of course, that the invention is susceptible of various changes and modifications which may be made from time to time without departing from the real spirit or general principles thereof and it is accordingly intended to claim the same broadly, as well as specifically, as indicated in the appended claims.

What is claimed as new and useful is:—

1. In a reconditioned drum of the character described, having a perforation in a wall thereof, an interiorly threaded split annulus adapted to be manipulated into flatwise engagement with the inner surface of said perforated wall, and an exteriorly threaded bushing engageable with said annulus and having a radial flange adapted to overlie the outer surface of said drum marginally surrounding said perforation, said flange coacting with said annulus to clamp therebetween the portion of the drum wall marginally surrounding the perforation therein.

2. In a reconditioned drum of the character described, in combination, a drum having a perforation in one of the walls thereof, an eccentrically apertured disk disposed flatwise against the inner surface of said wall with the aperture thereof in registry with the perforation in said drum wall, the aperture in said disk being interiorly threaded for threadedly receiving a flanged bushing and the marginal wall of said aperture being split approximately at the point of its least radial dimension to permit free insertion of the disk through the drum perforation without requiring the diameter of the disk aperture to be less than that of the drum perforation, and a flanged bushing threadedly engaging said disk whereby to clamp the portion of the drum wall marginally surrounding the perforation therein between the bushing flange and the apertured disk.

3. In a reconditioned drum of the character described, in combination, a drum having a perforation in one of the walls thereof, an eccentrically apertured disk the marginal wall of which is split approximately at the point of its least radial dimension to provide a pair of terminal extremities spaced apart sufficiently to permit the disk to be slipped through said perforation into a position overlying the inner surface of said perforated wall, the diameter of the disk aperture being approximately the same as and the overall diameter of said disk being considerably greater than the diameter of said perforation, and a bushing directly engaging said disk to clamp therebetween the portion of the drum wall marginally surrounding the perforation therein.

4. In a drum of the character defined in claim 3 wherein the aperture in said disk is interiorly threaded and wherein the bushing is exteriorly threaded for threaded reception within said aperture.

CHARLES E. FARRINGTON.
